UNITED STATES PATENT OFFICE

140,426

DESIGN FOR A MOTION PICTURE PROJECTOR

Otto R. Nemeth, Chicago, Ill., assignor to Products
Development, Inc., Chicago, Ill., a corporation
of Illinois

Application December 23, 1944, Serial No. 117,049

Term of patent 14 years

(Cl. D61—1)

To all whom it may concern:

Be it known that I, Otto R. Nemeth, a National of Czechoslovakia, residing at Chicago, in the county of Cook and State of Illinois, have invented a new, original, and ornamental Design for a Motion Picture Projector, of which the following is a specification, reference being had to the accompanying drawings, forming part thereof.

Figure 1 is a side elevational view of a motion picture projector showing the essential features

of my design in full lines, one of the film carrying reels being shown broken away for convenience of illustration.

Fig. 2 is a front elevational view of the projector.

Fig. 3 is a rear elevational view of the projector.

I claim:

The ornamental design for a motion picture projector, substantially as shown and described.

OTTO R. NEMETH.
